(57) **CLAIM**

The ornamental design for a traveling spool holder, as shown and described.

DESCRIPTION

FIG. 1 is a perspective view of a traveling spool holder, showing my new design in an unfolded configuration.

FIG. 2 is a front elevational view of the invention in the unfolded configuration;

FIG. 3 is a rear elevational view of the invention in the unfolded configuration;

FIG. 4 is a left-side elevational view of the invention in the unfolded configuration;

FIG. 5 is a right-side elevational view of the invention in the unfolded configuration;

FIG. 6 is a top plan view of the invention in the unfolded configuration;

FIG. 7 is a bottom plan view of the invention in the unfolded configuration; and,

FIG. 8 is a right-side elevational view of the invention, illustrating the invention in a folded configuration.
